(57) **CLAIM**

The ornamental design for beverageware as shown and described.

DESCRIPTION

FIG. 1 is a front, top, right perspective view of a first embodiment of beverageware showing my new design;
FIG. 2 is another front, top, right perspective view thereof, with the base of the beverageware removed;
FIG. 3 is a front elevational view thereof;
FIG. 4 is a rear elevational view thereof is a front elevational view thereof;
FIG. 5 is a left-side elevational view thereof;
FIG. 6 is a right-side elevational view thereof;
FIG. 7 is top plan view thereof;
FIG. 8 is bottom plan view thereof;
FIG. 9 is a perspective view of a second embodiment of beverageware showing my new design;
FIG. 10 is another perspective view thereof, with the base of the beverageware removed;
FIG. 11 is a front elevational view thereof;
FIG. 12 is a rear elevational view thereof is a front elevational view thereof;
FIG. 13 is a left-side elevational view thereof;
FIG. 14 is a right-side elevational view thereof;
FIG. 15 is top plan view thereof; and,
FIG. 16 is bottom plan view thereof.

The evenly spaced broken lines in the figures depict portions of the beverageware that form no part of the claimed design. The long-dash, short-dash lines represent the unclaimed boundary of the claimed design.
